Primary Examiner — Llorellys Martinez(74) *Attorney, Agent, or Firm* — Knobbe, Martens, Olson & Bear, LLP(57) **CLAIM**

The ornamental design for a building extrusion, as shown and described.

DESCRIPTION

FIG. 1 is a front end view of a building extrusion, showing our new design;

FIG. 2 is a back end view thereof;

FIG. 3 is a left side elevational view thereof;

FIG. 4 is a right side elevational view thereof;

FIG. 5 is a bottom plan view thereof;

FIG. 6 is a top plan view thereof; and,

FIG. 7 is a front, top and left side perspective view thereof. The building extrusion is shown with a symbolic break in its length. The appearance of any portion of the building extrusion between the break lines forms no part of the claimed design.
